Filed July 20, 1971, Ser. No. 164,486

Term of patent 14 years

Int. Cl. D12—15

U.S. Cl. D12—151

FIG. 1

FIG. 2

FIG. 3

FIG. 4

FIG. 1 is a front perspective view of a tire showing my new design.

FIG. 2 is a side elevation thereof.

FIG. 3 is a fragmentary front elevation view of the tire disclosed in FIG. 1, it being understood that the tire design continues repetitively and uninterruptedly around the circumference of the tire.

FIG. 4 is a cross-section taken on line 4-4 in FIG. 3.

I claim:

The ornamental design for the tire, as shown and described.
